US00D673833S

(12) **United States Design Patent**
Kay

(10) **Patent No.:** **US D673,833 S**
(45) **Date of Patent:** **** Jan. 8, 2013**

(54) **SHARPENER**

(75) Inventor: **Neil J. Kay**, Rolling Hills Estates, CA
(US)

(73) Assignee: **Cisco Sales Corp. (USA)**, Torrance, CA
(US)

(**) Term: **14 Years**

(21) Appl. No.: **29/374,090**

(22) Filed: **Jul. 5, 2011**

(51) **LOC (9) Cl.** **08-05**

(52) **U.S. Cl.** **D8/93**

(58) **Field of Classification Search** **D8/63,**
D8/90-94; 76/82, 84, 86-89; 451/552, 555-558
See application file for complete search history.
